UNITED STATES PATENT OFFICE.

LUTHER B. ZILAR, OF MIAMI, OKLAHOMA.

GRATE HOUSING.

Application filed August 4, 1926. Serial No. 127,119.

This invention relates to a housing for basket grates and the like for use for heating purposes.

One of the objects of the invention is to provide a housing which can be placed at any desired point within a room or other enclosure, said housing holding a grate in such a manner that practically all dangers resulting from the use of fuel in an open grate are eliminated, means being employed for controlling the flames so that they will not enter the chimney, to which the housing is connected.

A further object is to utilize baffles which, by deflecting the flames, also conserve heat and render the grate more efficient as a heating medium.

A further object is to provide a structure of this character which can be cleaned readily.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a front elevation of a housing constructed in accordance with the present invention.

Figure 2 is a section on line 2—2, Figure 1.

Figure 3 is a section on line 3—3, Figure 2.

Referring to the figures by characters of reference 1 designates a housing preferably formed of sheet metal. This housing is open at the bottom where it is provided with air inlet apertures 2 in the front wall. The space within the lower portion of the housing is sufficiently large to receive a basket grate G, andirons, a gas burner, or the like. The rear portion of the top of the housing is provided with an outlet 3 from which products of combustion will escape through a suitable pipe into a chimney. Extending transversely within the housing is a series of superposed baffle plates 4, these plates having downturned flanges 5 which are riveted or otherwise secured to the sides and back of the housing. The baffles are preferably inclined

downwardly and forwardly although their forward edges are spaced from the front wall of the housing. Secured to the front wall of said housing and to the side walls are downturned flanges 6 of another series of superposed baffles 7, these baffles being inclined downwardly and rearwardly and being extended between but spaced from the baffles 4. A concave reflector in the form of a plate 8 is secured to the lower baffle 4 and to the back wall of the housing so that products of combustion coming thereagainst will be deflected into the lower end of the tortuous passage formed by the baffles 4 and 7 while the light rays will be reflected downwardly and forwardly.

Formed within the front of the housing close to the top of each of the baffle plates 7 is a cleanout opening 9 and each cleanout opening is normally closed by means of a damper 10 pivotally connected to the front of the housing as shown at 11.

The front of the housing 3 is provided, below the lower baffle plate 7 with an opening 12 adapted to be closed by doors 13. These doors are preferably removably mounted, there being a longitudinal groove 14 in the lower edge portion of each door designed to receive the bottom wall of the door opening as shown in Figure 2 while latches indicated generally at 15 can be employed for fastening the upper portions of the doors in closed positions.

By lifting the doors 13 from the opening 12 fuel can be placed in the grate G and by leaving the door opening uncovered, the heat from the burning fuel will radiate directly through the opening 12. The products of combustion will pass upwardly between the baffles, being compelled to follow a tortuous path. These baffles will prevent the flame from entering the outlet 3 and will absorb much of the heat escaping upwardly. This heat will be conducted through the baffles to the walls of the structure and radiate therefrom, thus increasing the efficiency of the heater. By leaving the doors 13 closed there is no danger of sparks flying forwardly through the opening and igniting articles in close proximity to the housing.

The baffles can be cleaned readily by shifting the dampers 10 and inserting cleaning devices through the openings 9.

It is to be understood of course that this structure can be suitably ornamented and in

the device illustrated a foot rail 16 is shown along the lower portion of the front of the housing.

What is claimed is:

- 5 A device of the class described including a housing open at the bottom and having an outlet aperture at the top, there being a door opening in the front of the housing adjacent the bottom, a closure for the door opening;
- 10 a series of superposed baffle plates within the housing secured to the front thereof, a series of superposed baffle plates within the housing and secured to the back thereof, the baffle plates of one series being extended be-

tween the baffle plates of the other series, 15 said plates cooperating to provide a tortuous passage for combustion products, a combined deflector and reflector connecting the lower baffle of one series to the back wall of the housing, there being clean-out openings 20 in the front wall of the housing adjacent the baffles of the front series, and closures for said openings.

In testimony that I claim the foregoing as my own, I have hereto affixed my signature.

LUTHER B. ZILAR.
